(57) **CLAIM**

The ornamental design for a clip, as shown and described.

DESCRIPTION

FIG. 1 is a front view of a clip showing our new design, the rear view thereof being a mirror image;

FIG. 2 is a left side view thereof, the right side view thereof being a mirror image;

FIG. 3 is a top plan view thereof;

FIG. 4 is a bottom plan view thereof; and,

FIG. 5 is a front perspective view thereof.

The broken lines shown in the drawings represent portions of the clip that form no part of the claimed design.
